UNITED STATES PATENT OFFICE.

HARRY H. KONERMAN, OF NEWPORT, AND FREDERICK E. WERGES, OF LUDLOW, KENTUCKY, ASSIGNORS TO THE GLOBE REGISTER COMPANY, OF CINCINNATI, OHIO, A CORPORATION OF OHIO.

AUTOGRAPHIC REGISTER.

1,326,406.

Specification of Letters Patent.

Patented Dec. 30, 1919.

Application filed August 14, 1919. Serial No. 817,560.

To all whom it may concern:

Be it known that we, HARRY H. KONERMAN and FREDERICK E. WERGES, citizens of the United States of America, and residents of Newport and Ludlow, respectively, in the counties of Campbell and Kenton and State of Kentucky, have invented a new and useful Improvement in Autographic Registers, of which the following is a specification.

The object of our invention is a simple and accurate means for feeding forward predetermined lengths of the sheets of paper in an autographic register.

15 This object is attained by the means described in the specification and illustrated in the accompanying drawings in which:

Figure 1 is a transverse sectional view of an autographic register showing the paper feed mechanism embodying our invention. Fig. 2 is a longitudinal sectional view taken on line 2—2 of Fig. 1. Fig. 3 is a plan view of a piece of the paper used in the autographic register embodying our invention.

25 The autographic register embodying our invention comprises a feed shaft A upon which is secured feed rollers a, a¹, in positions such that they register with supporting rollers B, B¹ and when the feed shaft 30 is rotated co-act with the supporting rolls B, B¹ in feeding the sheets of paper forward, while the imperforate parts of the sheet are between said rollers, but which cease to be operative when the perforations d, d¹, in the webs D register with the rolls. To start the feed of the paper again, we have provided a starting roll E, which is mounted loosely upon feed shaft A, and which may be shifted thereon to cause its finger e to engage the 35 teeth of a pinion F which is secured upon feed shaft A. The means for shifting the roll E is a bar g which is mounted reciprocally upon the under side of the casing H and has a lug g¹ which engages a groove e¹ in the roll E. For shifting the bar g, we have provided a handle G which projects through slots in the casing and engages the bar g. A spring g², normally holds the bar in position such that the roll E is disengaged from the pinion F.

45 Roll E is of a diameter such as to hold the sheets of paper D in contact with the supporting roll B². Roll E has a flattened portion e². When this flattened portion con-

tacts with the paper, the paper is not held 55 in contact with the supporting roll, B², so that there is no tendency to bind roll E upon its shaft and cause it to rotate.

Feed shaft A is driven from the drive shaft K by a pinion k which meshes with a 60 pinion a² which is secured upon feed shaft A. Drive shaft K has secured upon its outer end a crank h¹, by means of which it may be turned. Upon the shaft K the supporting 65 rolls B, B¹, B² are secured.

In operation, to start the feed of the paper handle G is moved to bring finger e into engagement with pinion F. This imparts rotation to the roll E, and causes the circular part of its periphery to feed the paper 70 forward, so that the feed rolls a, a¹, press the paper against the rolls B, B¹. Then the rotation of the feed shaft A, will feed the paper forward. As soon as the feed rolls a, a¹ get a grip upon the paper, handle G is 75 released and the spring g² carries the roll E to its normal position, out of engagement with the pinion F. Feed rolls a, a¹ will feed the paper forward until the next row of 80 perforation d, d¹ thereon register with the feed rolls. The turning of the feed shaft A then has no effect upon the paper. If it be desired to feed another set of tickets forward starter E must be brought into operation as hereinbefore described. 85

What we claim is:

1. In an autographic register the combination of supporting rolls, a feed shaft, rolls supported upon the feed shaft in registration with some of the supporting rolls and adapted to contact with said supporting rolls in feeding paper, a starter roll mounted loosely upon the feed shaft adjacent to the other of the supporting rolls and a mechanism adapted to shift the starter roll to a 90 position in which it becomes fixed upon its shaft and registers with said other supporting roll.

2. In an autographic register the combination of supporting rolls, a feed shaft, feed 100 rolls secured upon the shaft in registration with some of the supporting rolls, a starting roll mounted loosely upon the feed shaft, clutch members for securing the starting roll upon the feed shaft, the clutch members 105 being so located in relation to one of the supporting rolls that when they fix the starting roll upon the shaft, the starting roll

is in registration with one of the supporting rolls.

3. In an autographic register the combination of paper supporting rolls, a feed shaft, 5 feed rolls secured upon the feed shaft in registration with some of the supporting rolls, a starting roll having clutch members adapted to fix the starting roll upon the feed shaft, a spring normally holding the

clutch members separated, and a means for shifting the clutch members into engagement with each other.

In testimony whereof, we have hereunto subscribed our names this 7th day of August, 1919.

HARRY H. KONERMAN.
FREDERICK E. WERGES.
